UNITED STATES PATENT OFFICE.

GEORGINA A. JOHNSTON, OF LOS ANGELES, CALIFORNIA.

VENDING MACHINE.

Application filed December 6, 1923. Serial No. 673,868.

To all whom it may concern:

Be it known that I, GEORGINA A. JOHNSTON, a citizen of the United States, residing at Los Angeles, in the county of Los Angeles and State of California, have invented a certain new and useful Improvement in Vending Machines, of which the following is a full, clear, and exact description, reference being had to the accompanying drawings.

This invention relates to vending machines and particularly to vending machines which are adapted to be used with toilets for providing a seat cover which may be placed on the toilet seat for each successive user.

A further object of the invention is to provide a vending machine which operates to feed a sheet of paper from the machine to an operative position after which the machine again operates to remove the paper from its first position.

One object of the invention is to provide a machine adapted for use with toilets, wherein the machine first feeds a sheet of paper to a toilet seat and later removes the sheet from the seat to a receptacle where the sheet may be burned.

A further object of the invention is to provide an automatic machine for feeding seat covers to a toilet seat and then removing the sheet from the seat.

Other objects of the invention will be apparent from the following specification taken in connection with the accompanying drawings wherein Fig. 1 is a central sectional view through a machine embodying the features of my invention showing certain of the operating parts in elevation; Fig. 2 is a view similar to Fig. 1 taken on a different plane and showing other parts of the operating mechanism; Fig. 3 is a section taken through the front of the casing at right angles to the views shown in Figs. 1 and 2 and showing the operating parts in elevation; Fig. 4 is a fragmentary detail of the casing showing an electrical connection; Fig. 5 is a fragmentary detail showing the spring means for closing the circuit when the paper container is empty; Fig. 6 is an elevation of a link of the chain used for propelling the paper showing the paper engaging dog in elevation; Fig. 7 is a section through the guard for the chain showing the chain in section and the paper engaging dog in elevation; Fig. 8 is an enlarged view similar

to Fig. 7 showing the cam for causing movement of the paper engaging dog toward the paper; Fig. 9 is a top plan of the coin slide and circuit closer adapted for use with my invention; Fig. 10 is a top plan of the circuit closer operated by the coin slide; Fig. 11 is a side elevation of the circuit closer; Fig. 12 is a sectional detail showing the chain conveyor and guard for removing the paper; Fig. 13 is a detail of one of the circuit closers; Fig. 14 is a plan of the paper adapted for use with my invention; Fig. 15 is a perspective view showing the installation of my vending machine; Fig. 16 is a detail of a door for the receptacle and Fig. 17 is a wiring diagram.

Referring to the drawings by reference characters, I have shown at 10 a casing which may be made of sheet metal. Arranged within the upper part of the casing I show a receptacle 11 for sheets of paper. The receptacle 11 is provided with an inclined bottom so that the sheets of paper 12 are arranged with their adjacent lower edges disposed one in advance of the other.

A feed roll is shown at 14. This feed roll is spaced from the edge 15 of the mouth of the receptacle a distance substantially equal to the thickness of one sheet of paper. As a result when the roll 14 is rotated only one sheet of paper can be removed from the receptacle at one time. The roll 14 is preferably provided with a spaced friction means, such as rubber strips, arranged thereon to facilitate the feeding of the paper.

Extending from the said roll 14 I show a passageway 17 for the sheets of paper. The reach 18 of the passageway 17 is so arranged as to direct the sheet being fed by this roll 14 between the rolls 19 and 20. The rolls 19 and 20 are arranged to feed the paper through an aperture 21 in the front of the casing onto a table 22.

The front of the paper receptacle 11 is provided with a follower 23 which is urged toward the rear of the receptacle by springs 24 so that as the supply of paper diminishes the follower moves toward the back of the casing for a purpose to be presently described.

By referring to Fig. 15 of the drawing the arrangement of the vending machine with respect to the toilet seat will be noted. The casing 10 is preferably removable held in place by brackets or cleats 25 arranged on a partition 26. A flush tank for the

toilet is shown at 26'. The toilet seat is shown at 27. This seat is preferably of the well known type wherein it is normally held above the toilet and swings down under the 5 weight of the user. The seat engages a pivoted lever 27' which is mounted on the casing 10.

When the paper is fed forward by the 10 rolls 19 and 20 it advances over the table 22 onto the toilet seat 27. The paper is made of such a length that when it has been advanced by the rolls 19 and 20 until its end has passed between these rolls it will be 15 properly fitted over the seat.

15 After use it is desirable to provide automatic means for removing the sheet of paper 12 from the seat. To bring this about I provide mechanism so that when the seat is raised the operation causes the motor 20 to rotate the shaft 30. The shaft 30 has a pair of spaced sprockets 31 thereon, each of which receives a chain 32. Sprockets 33 mounted adjacent the table 22 have the chains 32 passing thereover. The chains are 25 shown in Figs. 6, 7 and 8 on an enlarged scale and it will be noted that certain links are provided with locking dogs 35. I prefer to use two pairs of the locking dogs but more or less may be used as desired. Each 30 dog is normally held in retracted position by a spring 36. A suitable guard 38 is provided for the chain 32.

I prefer to space the chains apart laterally so that the sheet of paper 12 passes 35 between them thus enabling the dogs 35 to move towards each other until the ends 40 thereof engage the sheet.

In order to move the locking dogs toward 40 each other I show guides 41, through which the chains 32 pass, as provided with a cam surface 42 which is arranged on the inner 45 surface of the guides and which is adapted to engage the dogs 35 to force them toward each other. The cams 42 extend from the point 43 to the point 44 where they terminate so that the article being conveyed will 50 be released. The sprocket 31 it will be noted by referring to Fig. 2 is arranged within a container 45 which is disposed in the bottom of the casing 10. The chains pass through a narrow slot in the front of the container 45.

55 My improved vending machine may be operated in any desired manner but I now prefer that its actuation be automatic and that the operation of the machine be controlled by coins or tokens which may be inserted by the user. I will now describe one form of mechanism which is adapted to operate the machinery for delivery of the articles and their removal.

60 Referring to Fig. 9 I show a plan of the coin mechanism while in Fig. 1 a side elevation of this mechanism is disclosed. The sliding member 50 is provided with a pair

of opposed apertures 51 and with a bottom plate 52. Suitable coins may be inserted in the apertures 51 and when the slide 50 is pushed into the casing the coins make contact with the spring terminals 53 and 54 and 70 the circuit is completed through the coins and through the plate 52. The terminals 53 and 54 are connected respectively with leads 55 and 56. The slide 50 is provided with an operating member 57 which is connected to 75 a circuit closer 58 pivoted at 59 to the casing 10. The circuit closer 58 completes the circuit through the terminals 60 and 61 to a lead 62 which is connected to another lead 63 communicating with a source of power. 80

From the description it will be apparent that when the proper coins have been placed in the two apertures 51 and the slide 50 is pushed inwardly, that the circuit closer 58 will close the circuit through the leads 85 62 and 55 and that the coins in the apertures 51 will close the circuit from the lead 55 to the lead 56. The lead 56 communicates with the terminal 65 of a motor 66 which has a second terminal 67 connected by a lead 90 68 with the return lead 69.

It will thus be seen that when the slide 50 is moved inwardly, with the proper coins inserted, that the motor will begin operation. 95

By referring to Fig. 3 it will be seen that the motor 66 is provided with a gear 67 which meshes with a second gear 68 shown as engaging another gear 69. The gear 69 is mounted on a shaft 70 which is provided 100 with a gear 71 meshing with another gear 72 which in turn drives a gear 73 arranged on a shaft 74. The feed roll 14 previously described is arranged upon the shaft 74 so that the operation of the motor 66 causes 105 the feed roll 14 to rotate.

The gear 71 also engages a gear 75 shown as engaging a gear 76. The gears 75 and 76 are keyed to shafts 77 and 78 and upon the shafts 77 and 78 I arrange the feed 110 rolls 19 and 20. The shaft 70 is also provided with a one-toothed gear 80 thereon. This one-toothed gear engages a second gear 81 having peripheral teeth so arranged that for each rotation of the gear 80 the gear 81 will be rotated for a partial revolution. The gear 81 is shown as mounted on a shaft 82, which is provided with a disc 83 (see Fig. 17) having a circular contact member 84 thereon. The contact member is electrically connected with a lead 85 which is connected to the lead 56. The contact 84 is arranged about the disc 83 so as to make practically a complete circle thereon. The ends of the contact 84 are spaced about a distance slightly greater, however, than the width of a contact member or brush 90. The contact 90 is connected by means of a lead 91 with the lead 63.

When the motor is operated through the 130

movement of the slide 50 the operation thereof drives the shaft 82 and closes the circuit between the contact 90 and the contact 84 so that the circuit is complete to the motor 5 through the lead 63, lead 91, contact 90, contact 84, to lead 85, lead 56, terminal 65, terminal 67, lead 68, to the return line 69.

The slide 50 is provided with a spring 70 to cause it to return to normal position after 10 it has completed the circuit and started the motor. The feeding mechanism continues to function with the rolls 14, 19 and 20 rotating and advancing the paper until the shaft 82 has made a complete revolution 15 and until the contact 84 is freed from the contact 90. This action causes the sheet of paper or article being vended to be removed from the receptacle 12 through the passageway 17 and through the discharge 20 apertures 21 to and over the table 22.

To effect a reverse movement of the article by means of the chains 32 in the manner previously described I prefer to construct the motor 66 as a reversible motor and to 25 provide a ratchet member 100 on the gear 69 for clutching this gear to the shaft 70. The ratchet 100 is so arranged that the gear 69 will drive the shaft 70 only when the gear rotates in one direction.

30 The operating member 27', previously described, is pivoted to the casing 10 as shown in Fig. 1 and is provided with a trip mechanism 110 which is so arranged that as the forward part of the operating member 27' moves downwardly the trip member moves upwardly and passes idly over the operating portion 112 of a circuit closer 114. When the operating member 27' moves upwardly the trip 110 moves down 40 and engages the closer 114, and turns it about its pivot 115 to bring the contact member 116 thereon in contact with the spaced terminals 117 and 118.

By referring to Fig. 17 where the switch 45 is shown diagrammatically it will be seen that the movement of this switch closes the circuit at the contacts 117 and 118 to close the circuit through the leads 123 and 124. This completes the circuit through lead 63, lead 123, switch 114, lead 124, motor terminals 125, motor terminal 126 and lead 69. This action causes the motor to reverse thus rotating the shaft 30 through gears 130 and driving the chains 32. A contact 55 disc 131 is mounted on a shaft 132 which is driven from the gears 130 when the motor is reversed. During forward movement of the motor the gears 130 are stationary being clutched to the motor shaft only when the motor is reversed.

The contact disc 131 has a contact member 132' thereon similar to the contact member 84 and is also provided with a brush 133 similar to the brush 90. The brush 133 is 60 connected by a lead 134 with the lead 63

while the contact ring 132' is connected by a lead 136 with the terminal 125 of the motor.

It will thus be apparent that when the switch 114 closes the circuit to reverse the 70 motor that the motor will continue its reverse motion until the disc 131 has made substantially a complete revolution.

In order to prevent the loss of coins by the operator in the event that the supply of 75 paper in the container is exhausted I show the receptacle 12 as provided with an insulated contact member 150. The follower 23 which may be made of metal is engaged by the spring contact 24 which is electrically 80 connected at 151 with the front of the casing. When the supply of articles is exhausted the follower will move toward and engage the rear wall closing the contact through the lead 150' and the spring 24 to a lead 85 153. The lead 153 is connected across a lamp 154 with a lead 155 in circuit with the lead 63. The casing is provided with an aperture 156 in which the lamp 154 is contained and the front of the aperture 156 90 may be provided with a transparent panel having the word "Empty" thereon so that when the supply of articles is exhausted the lamp 154 will illuminate the sign. The completion of the circuit across the terminals 95 150 and 153 completes the circuit through 156 to the magnet 157, lead 158, terminal 61 and 60, and lead 62 so that the magnet exerts a pull on the armature 160 thereby rocking the lever 161 and also rocking 100 the bell crank 162. The bell crank is provided with a closure 163 pivoted thereto in such a manner that when the lever 161 is rocked the valve 163 will swing to the right in Fig. 1 closing the passage 165 to the coin receptacle 166 and directing the coin to the passage 167 and the cup 168 where the operator may secure his coin. It

may here be explained that when the coins are conveyed inwardly by the slide 50 they pass beyond the end of the bottom 52 of the slide and then drop into the chute 52'.

In order to dispose of the paper removed from the seat 27 I show the lower portion 110 of the casing 10 as provided with an incinerator 170. This incinerator is connected by means of leads 171 and 172 with contact members 174 and 175, arranged along the side wall of the guard 38. The contacts 174 and 175 are spaced apart so that normally 115 the circuit is open and the incinerator is not in operation. Mounted upon the links of the chain 32 which are provided with the dogs 35, I show contact members or circuit closers 176. These circuit closers are arranged to close the circuit between the leads 171 and 172 and thus cause the coils of the incinerator to be heated. The contacts 174 and 175 extend from about the point 43 to 120 about the point 44 so that while the chains 125 130

- 32 are conveying the paper between these points the incinerator is operating to consume sheets previously delivered by the chains.
- 5 In circuit with the leads 171 and 172 I show a motor 178 which is arranged in a flue 179. The flue is provided with an exhaust opening 180 to the air and with a passage 181 leading to the chamber 182 which houses the incinerator.
- 10 The movement of the chains 32 causes the circuit to the motor 178 to be closed so that the fan draws the smoke and fumes from the particles being consumed out through the passage 181. Should any solid particles be accidentally delivered to the incinerator the fan will draw such particles through the passage 181 whence they will fall to the removable receptacle 185.
- 15 In order to provide a convenient supply of small paper and at the same time to provide means for preventing waste thereof I arrange the small paper on a roll 190 which is fixed on a shaft 191. The shaft 191 has a toothed ratchet 192 secured thereto. Mounted adjacent the ratchet I show a locking pin 193 which engages the ratchet 192 to normally prevent rotation of the shaft 191 and consequent rotation of the paper roll.
- 20 The locking pin 193 is shown as connected by means of a bell crank 194 with an operating lever 195 which is preferably arranged to be engaged by the operating member 27' associated with the toilet seat. A spring 196 normally pushes the operating lever 195 downwardly as shown in Fig. 1 thus preventing rotation of the paper roll.
- 25 When the toilet seat is lowered and the operating arm rocked the portion 197 thereof engages the lower end 198 of the operating member 195 and pushes the latter upwardly thus disengaging the locking pin 193 and allowing the paper to be unrolled from the roll.
- 30 In Fig. 16 I show the details of a door which may be provided in the casing 10 just above the incinerator so that articles to be burned may be inserted in the incinerator chamber. The door may comprise a container 200, of cylindrical form, having an opening 201 and having an operating knob 202. The door may be hung on a shaft 203 which is inserted through the front and back of the casing 10.
- 35 One of the seat covers which may be used with my improved vending machine is shown in Fig. 14 as comprising a body part 12 having opposed apertures 210 defined by straight sides and curved ends. A tongue 211 which is perforated at 212 to facilitate tearing is provided in the seat cover. The cover is preferably creased at 214 to allow it to be bent down over the edges of the seat after the tongue 211 is broken.
- 40 I claim:
1. In combination with a toilet including a seat, a receptacle for paper, means to feed said paper from said receptacle over said seat in one direction, means to stop said sheet feeding means, and additional means for removing said sheet from said seat in a direction opposite to the first mentioned direction and in the same plane. 70
2. In a toilet, a receptacle for holding a plurality of sheets of paper, means to feed said sheets of paper singly from said receptacle, a seat, means to advance said sheets of paper over said seat, means to stop said sheet advancing means and means for removing the sheet of paper from said seat in a direction opposite to the advancing movement. 75
3. In a toilet having a seat, a casing, a plurality of sheets of paper in said casing, a passageway from said casing to said seat, means for engaging a sheet of paper and moving it from said casing to said seat, a receptacle in said casing, and means for moving said paper from the seat to said receptacle in a direction reverse to the first mentioned direction but in the same plane. 80
4. In combination with a toilet having a seat, a casing, a plurality of sheets of paper arranged in said casing, a passageway from said casing to said seat, a receptacle in said casing, and means for first advancing paper over said seat and for thereafter removing the paper from said seat, said last means being controlled by the operation of said seat. 85
5. In combination with a toilet having a seat, a vending machine including a casing having a receptacle for a plurality of sheets of paper, means to deliver said sheets of paper from said receptacle, means to advance said sheets of paper from said receptacle to said seat, and means actuated by the movement of said seat to remove said sheets of paper from said seat. 90
6. In combination with a toilet having a seat, a vending machine, a receptacle for paper therein, means to feed said sheets of paper from said receptacle one at a time, a channelway extending from said feeding means, a pair of rolls for advancing said sheets to said seat, means for removing said sheets from said seat, said last mentioned means comprising pairs of spaced sprockets having chains thereon, means carried by said chains for engaging said sheets, means whereby the engagement of said last mentioned means is effected by the movement of said chains and means for releasing said sheet from said chains. 110
7. In a vending machine, a receptacle for articles to be vended, a table, means to feed said articles singly from said receptacle to said table, a motor for operating said feeding means, two independent circuits to the motor, one of said circuits when closed causing said motor to operate forwardly and the 115
8. In a vending machine, a receptacle for articles to be vended, a table, means to feed said articles singly from said receptacle to said table, a motor for operating said feeding means, two independent circuits to the motor, one of said circuits when closed causing said motor to operate forwardly and the 120
9. In a vending machine, a receptacle for articles to be vended, a table, means to feed said articles singly from said receptacle to said table, a motor for operating said feeding means, two independent circuits to the motor, one of said circuits when closed causing said motor to operate forwardly and the 125
10. In a vending machine, a receptacle for articles to be vended, a table, means to feed said articles singly from said receptacle to said table, a motor for operating said feeding means, two independent circuits to the motor, one of said circuits when closed causing said motor to operate forwardly and the 130

- second of said circuits when closed causing said motor to operate rearwardly, means whereby said first circuit can be closed to cause said motor to operate said feed means 5 to feed sheets to said table, means to close said second circuit to reverse said motor, and means operated by the reverse movement of said motor to convey sheets from said table.
- 10 8. In a vending machine, a receptacle for sheets of paper, a table, a delivery chute from said receptacle to said table, means to feed sheets of paper from said receptacle to said table, a motor, means whereby said motor operates said feeding means, a second receptacle, means to convey sheets of paper from said table to said second receptacle, said last mentioned means comprising a pair of spaced chains comprising links, certain of 15 said links having pivoted dogs thereon, said dogs being normally disposed with their ends beyond the side edges of the paper, means whereby the movement of said chains causes said dogs to move inwardly to engage said paper, and means to thereafter release said paper from engagement with said dogs.
- 10 9. In a vending machine, a receptacle for articles to be vended, a table, means to feed 20 said articles singly from said receptacle to said table, a motor for operating said feeding means, two independent circuits to the motor, one of said circuits when closed causing said motor to operate forwardly and the second of said circuits when closed causing said motor to operate rearwardly, an operating member for closing said first circuit to cause said motor to operate said feed means, means actuated by said motor to deliver said 25 articles fed by said feeding means to said table, a second receptacle, a second operating member adapted to close said second circuit to reverse said motor, and means operated by the reverse movement of said motor 30 to convey articles from said table to said second receptacle.
- 10 10. In a vending machine, a receptacle for holding a plurality of sheets of paper, means to feed said sheets of paper from said receptacle, a table, means to advance said paper to said table, a second receptacle, and means to advance said paper from said table to said second receptacle, an incinerator in said second receptacle and means whereby 35 the advancement of said paper to said second receptacle actuates said incinerator, a flue extending from said incinerator, a fan in said flue and means whereby the ashes of the paper consumed by said incinerator may be removed from said second container through said flue.
- 10 11. In combination with a toilet having a seat, a vending machine, a receptacle for seat covers, a table, a second receptacle, means to feed seat covers singly from said 40
- first receptacle to said seat, means to thereafter feed seat covers from said seat to said second receptacle, a motor for operating said feeding means, two independent circuits to said motor, an operating member for closing one of said circuits to cause a seat cover to be fed to said seat, a second operating member associated with the toilet seat for causing said motor to actuate the means for feeding the seat covers from the seat to the 45 second receptacle and means whereby but one of said circuits can be closed at one time.
12. In combination with a toilet having a seat, a vending machine, a receptacle for sheets of paper, a delivery chute extending from said receptacle to said seat, means to feed paper from said receptacle to said seat, a motor, means whereby said motor operates said feeding means, a second receptacle, means to deliver articles from said seat to 50 said second receptacle, said last mentioned means being operated by said motor, said last mentioned means comprising a pair of spaced chains having means thereon for engaging said paper, means whereby the movement of said chains causes said engaging means to engage said paper, and means to thereafter release said paper from engagement with said means.
13. In combination with a toilet having a seat, a vending machine, a receptacle for sheets of paper, a delivery chute for said receptacle, means to feed articles from said receptacle to said seat, a second receptacle, means to deliver sheets from said seat to said 55 second receptacle, said last mentioned means comprising a pair of spaced chains having engaging means thereon, means whereby the movement of said chains causes said engaging means to engage said paper, an incinerator including heated coils and means whereby when said chains move said coils are heated.
14. In a vending machine, a table, a paper receptacle comprising a container having an inclined bottom, means to feed sheets of paper singly from said receptacle to said table, said means including a feed roll for engaging a sheet of paper adjacent one end thereof, a passageway extending from said feed roll, a pair of delivery rolls adjacent said passageway, said delivery rolls serving to advance the paper fed by the first roll, means to operate said feed roll and means whereby the operation of said feed roll and said delivery rolls is continued until the paper has passed beyond the delivery rolls.
15. In a vending machine, a casing, a table adjacent said casing, a container for paper, means to advance sheets of paper singly from said container to said table, means to remove sheets of paper from said table, said means comprising spaced chains having engaging members thereon, each of said engaging members including a cam operated 120
- 125
- 130

dog, a guard for said chains, a cam on said guard for causing said dogs to engage said paper, a second container and means whereby the chains deliver sheets from the table to the second container.

16. In a vending machine, a casing having a paper container therein, a table adjacent said casing, means to advance sheets of paper singly from said container to said table, means to remove sheets of paper from said table, said means comprising spaced chains having engaging members thereon, each of said engaging members including a cam operated dog, a cam for causing said dogs to engage said paper, a second container, means whereby the chains deliver sheets from the table to the second container, a heating coil in said second container, a circuit including said coil, spaced contacts adjacent said chain and circuit closing means on said chains for bridging said contacts to close said circuit.

17. In a vending machine, a casing, a table adjacent said casing, a container for paper, means to advance sheets of paper singly from said container to said table, endless conveyors to remove sheets of paper from said

table, a guard for said conveyor, a second container and means whereby the conveyor delivers sheets from the table to the second container, a heating coil in said second container, a circuit from said coil, spaced contacts in said circuit, a circuit closer carried by said conveyor for bridging said spaced contacts, an exhaust fan associated with said second container, and means whereby the closing of said circuit operates the exhaust fan.

18. In combination with a toilet having a seat, a vending machine having a paper container therein, means to advance seat covers from said container to said seat, a roll of paper in said machine, a shaft on which said roll is mounted, a ratchet on said shaft, a pin engaging said ratchet, an operating member for releasing said pin, a second operating member associated with said toilet seat and means whereby said pin frees said ratchet to permit unrolling said roll of paper only when the operating member associated with the toilet seat is actuated.

In testimony whereof, I hereunto affix my signature.

GEORGINA A. JOHNSTON.
